United States Patent Office

Des. 223,125
Patented Mar. 14, 1972

223,125

MOTION PICTURE PROJECTOR

James H. Sias, Rochester, N.Y., assignor to Eastman
Kodak Company, Rochester, N.Y.

Filed Sept. 30, 1970, Ser. No. 25,680

Term of patent 14 years

Int. Cl. D16—02

U.S. Cl. D61—1

FIG. 1

FIG. 2

FIG. 3

FIG. 1 is a front perspective view of the motion picture projector showing my new design;

FIG. 2 is a rear perspective view thereof; and

FIG. 3 is a bottom plan view thereof.

I claim:

The ornamental design for a motion picture projector, as shown.
